(57) CLAIM

The ornamental design for a tobacco box, as shown and described.

DESCRIPTION

FIG. 1 provides a top right front perspective view of a tobacco box showing our new design in a closed usage condition;

FIG. 2 provides a top plan view thereof;

FIG. 3 provides a bottom plan view thereof;

FIG. 4 provides a front elevation view thereof, the rear elevation view being a mirror image thereto; and,

FIG. 5 provides a right side elevation view thereof, the left side elevation view being a mirror image thereto.
